UNITED STATES PATENT OFFICE.

CONRAD FICHTNER, OF GOODRICH, NORTH DAKOTA.

SHAPING-TOOL.

No. 813,784.

Specification of Letters Patent.

Patented Feb. 27, 1906.

Application filed June 10, 1905. Serial No. 264,717.

To all whom it may concern:

Be it known that I, CONRAD FICHTNER, a citizen of the United States, residing at Goodrich, in the county of McLean and State of

5 North Dakota, have invented certain new and useful Improvements in Shaping-Tools, of which the following is a specification.

This invention consists of a simple tool for use in the operation of shaping or reshaping 10 plowshares either in the original manufacture thereof or after the share has gotten out of shape through hard service or otherwise.

For a full description of the invention and the merits thereof and also to acquire a 15 knowledge of the details of construction of the means for effecting the result reference is to be had to the following description and accompanying drawings, in which—

Figure 1 is a perspective view of a device 20 embodying the invention applied. Fig. 2 is a top plan view of the tool. Fig. 3 is a transverse section on the line X X of Fig. 2. Fig. 4 is a detail perspective view of one of the clamp-levers.

25 Corresponding and like parts are referred to in the following description and indicated in all the views of the drawings by the same reference characters.

Specifically describing the tool which comprises 30 this invention, the numeral 1 designates a holder adapted to receive the upper portion of the plowshare, (indicated at 2,) and said holder comprises the spaced members 1^a and 1^b, preferably consisting of longitudinal bars arranged in approximately parallel relation. The bars 1^a and 1^b of the holder 1 are connected at the ends, and said bars are also connected at points between the ends thereof by means of transverse connecting 35 members 3. The members 3 are preferably of somewhat U form and have the sides thereof riveted or otherwise substantially secured to the bars 1^a and 1^b at the outer sides of the latter. At one end of the holder 1 the bars 40 1^a and 1^b thereof are extended laterally to form a looped-shaped extension 4, so that the holder will snugly receive the upper portion of the share in an obvious manner. Mounted upon the members 3, which connect with

45 1^a and 1^b thereof are extended laterally to form a looped-shaped extension 4, so that the holder will snugly receive the upper portion of the share in an obvious manner. Mounted upon the members 3, which connect with 50 spaced members of the holder 1 and arranged longitudinally of the holder between said spaced members, is a transversely-movable clamp-bar 5, said bar being formed with openings 6 in the upper portion thereof, 55 through which pass the members 3 above mentioned. The clamp member 5 is trans-

versely movable, so that it may be forced toward the bar 1^b of the holder 1 to positively engage the upper portion of the share when the tool is operably mounted thereon. 60

Novel actuating means is used for effecting clamping action of the clamp-bar 5, and said means includes, primarily, a plurality of levers 6^a, 6^b, 6^c, and 6^d, having cams 7 at the lower ends adapted to engage the clamp-bar 65 5, so as to actuate the same. The lower ends of the levers aforesaid are bifurcated, preferably, one of the bifurcated portions being extended or curved from the other to form the cam members 7, which are adapted to operate between the bar 1^a of the holder 1 and the clamp-bar 5, said cams 7 being deflected laterally from a plane including the body of the levers, so that they may be forced into the space between the members 1^a and 5, 70 75 above described. The bifurcated portions of the levers adjacent the cams 7, which bifurcated portions are indicated at 8, have pivotal connection at the lower extremities thereof, as shown at 9, with the bar 1^a of the 80 holder, the pivot being upon the outer side of said bar or member 1^a.

It will be understood that any number of the levers above mentioned may be used within the contemplation of the invention, and 85 the cams 7 taper to a point at the lower ends thereof, being reduced transversely toward these extremities in order that these members will have the necessary cam action when the levers are operated to force the cams toward the clamp member 5 and the bar 1^a. 90 The end levers 6^a and 6^d are preferably longer than the intermediate levers 6^b and 6^c.

In the actual use of the invention the share 2 is first heated and the tool or device hereinbefore described is then applied, so that the upper portion of the share is received between the sides of the spaced members of the holder 1. The lever 6^a is then forced downwardly, then in succession the levers 6^b, 6^c, 100 and 6^d are operated in the same manner, the cams 7 being forced between the clamp-bar 5 to firmly engage with the share in a manner which will be apparent. The operator now takes a hammer or suitable tool and straightens out the share, after which the same is placed in cold water for hardening, and when hardened the tool may be removed. A stool or support 10 is illustrated in the drawings as means for supporting the share when the tool or device forming this invention is applied, 105 so as to prevent the share from falling. It 110

will be noted that the invention is very simple in its operation and embodies advantageous features which will be clear to those versed in the art to which the same appertains.

Having thus described the invention, what is claimed as new is—

1. In a tool of the class described, the combination of a holder embodying spaced longitudinal bars, members connecting said bars, a clamp member arranged between the longitudinal bars of the holder and mounted upon the members connecting said bars, and cam-levers arranged to coact with the clamp member to actuate the same.
2. In a tool of the class described, the combination of a holder embodying spaced longitudinal bars, members connecting said bars, a clamp member arranged between the longitudinal bars of the holder and mounted upon the members connecting said bars, levers pivoted to a side of the holder, and cams extended from said levers to engage between the clamp member and a side of the holder for actuating said clamp member.
3. In a tool of the class described, the com-

bination of a holder embodying spaced longitudinal bars, a loop extension at one end of the holder, a clamp member mounted between the longitudinal bars of the holder, and a plurality of cam-levers mounted upon the holder and arranged to coact with the clamp member.

4. In a tool of the class described, the combination of a holder consisting of spaced longitudinal bars, members connecting said bars at intervals between the ends thereof, a clamp-bar extending longitudinally between the bars of the holders and provided with openings through which the members connecting the bars of the holder pass, levers having one end bifurcated, one of the bifurcated portions of each lever being pivotally attached to the side of the holder, the other bifurcated portion being formed into a cam extension.

In testimony whereof I affix my signature in presence of two witnesses.
